UNITED STATES PATENT OFFICE.

ROBERT LAGUS, OF ABO, FINLAND, RUSSIA.

TELEPHONE FOR LONG DISTANCES OR FOR DEAF PERSONS.

1,239,702.

Specification of Letters Patent. Patented Sept. 11, 1917.

Application filed March 21, 1913. Serial No. 755,898.

To all whom it may concern:

Be it known that I, ROBERT LAGUS, a subject of the Emperor of Russia, residing at Abo, Finland, Russia, have invented certain new and useful Improvements in Telephones for Long Distances or for Deaf Persons, of which the following is a specification.

The present invention aims at enlarging the application of an ordinary telephone in operation between places widely separated from each other by providing an auxiliary apparatus so that conversation can be carried on with the telephone over much greater distances and with substantially greater clearness than is possible without this auxiliary apparatus. Moreover, the auxiliary apparatus can be employed for the purpose of strengthening the sounds at the farther telephone, if two telephones are embraced in the same line, and it renders the use of the telephone apparatus possible also for deaf people (over correspondingly shorter distances than for persons with normal hearing of course). The invention is based upon a proper combination of an ordinary telephone apparatus with the hearing device for deaf persons constructed according to the principles of a telephone.

As is well known, most telephone apparatuses are so arranged that two listening tubes can be attached to the same, and these are connected each with its pair of poles. In the present invention the listening tube for ordinary telephone conversations is connected to the one pair of poles, while the auxiliary apparatus is united with the second pair of poles. The telephone is, so to say, transformed into a double apparatus which, according to the manner of switching in, is either in condition to serve those of normal hearing for conversation over shorter distances or in condition for deaf persons over shorter distances or (and most important) for those with normal hearing over substantial distances.

The attached drawing illustrates several embodiments of the invention.

Figure 1 shows in front elevation the new device attached to a wall telephone of ordinary construction;

Fig. 2 shows the same in side elevation and with the contact pieces and switching device of the auxiliary apparatus partially

in section and separated from the contact pieces of the ordinary contact apparatus in order to show the manner of connection between both;

Fig. 3 is a vertical section through the box in which are the attached receiver of the ordinary telephone and the sound receiving and transmitting microphone of the auxiliary apparatus;

Fig. 4 is a vertical section through this casing seen along the line A—B from left to right;

Fig. 5 is a second vertical section through the same box looking along the line C—D from right to left;

Fig. 6 is an elevation of the receiving microphone, the cover and membrane being removed;

Fig. 7 is the end elevation of the device represented in Fig. 3 for moving the receiving microphone;

Fig. 8 illustrates a modification in detail of Fig. 1.

Referring to the embodiments of the invention illustrated, 1 is an ordinary wall telephone, and 2 is a combination transmitter and receiver connected with a pole couple 3. To a second pole couple 4 the auxiliary apparatus is attached, and this consists of a listening device for deaf persons, constructed according to the principles of a telephone.

The connection in the arrangement illustrated is carried out in the following manner. To the pole couple 4 there is attached a microphone receiver 5 by means of the conductors 6 and 7. The sounds coming out of this microphone receiver 5 are received by a microphone transmitter screwed onto the receiver or fastened to the same in any other manner. They are represented diagrammatically in Fig. 2 as separated from each other. They may be fastened in various ways, as for example in the adjustable fashion of Fig. 3. The microphone transmitter 8 is connected by means of a conductor 9 with a dry battery 10, of say 4 or 5 volts electromotive force, and by means of a conductor 11 with a listening tube 12, and from this a second conductor 13 leads to the second pole of the battery 10. By means of this construction sounds from the receiver 5 reach the listening tube 12 substantially increased. The listening tube 12 may be pro-

vided with a tube 14 screwed thereon and adapted to be inserted into the ear for the purpose of a better conduction of the sound.

By means of any usual or suitable devices (not shown in the drawing) the battery 10 may be cut out of the circuit when the apparatus is not in use by hanging the listening tube 12 on the hooked arm 15. There are employed for this purpose preferably the same devices as are generally employed with telephones.

Means are provided for uniting the receiving microphone 5, if necessary, completely with the listening tube or separating

15 the same from each other. A number of rather small conical holes are formed in the cover of the receiving microphone, which holes lie in a circle about the usual large hole in the middle. These improvements 20 render possible the application to the hearing apparatus of much stronger electric batteries than formerly, whereby a corresponding increase of the transmitted sounds can be obtained.

25 The receiver of the ordinary telephone is designated by 5 and the receiving microphone by 8. They are arranged opposite each other in a protecting box 16 with the geometrical axes in one and the same line. 30 The receiver 5 is fastened rigidly in the left portion of the casing in a manner not indicated further in detail. Opposite the receiver 5 there is arranged the receiving and transmitting microphone 8 in such a manner 35 that the same can be adjusted toward and away from the receiver 5 by means of a screw 17. The screw 17 extends through the back of the casing and is engaged by a nut 18 held in place by a strap 19. As the nut is 40 turned upward or downward the screw 17 is advanced or retracted. The hook 15 shown in Fig. 1 may be journaled upon the nut 18, Fig. 3.

45 As shown in the drawing, the transmitting microphone 8 shows some deviation from the ordinary microphone. It has a cover 20 with the usual large hole 21 in the middle and with a number of smaller holes 22 arranged approximately in a circle about the 50 large hole. In the preferred arrangement, as illustrated, the holes 22 are arranged in two concentric circles around the middle hole 21. These holes 22 are conical and, contrary to the middle hole 21, diverge toward 55 the membrane disk 23, as in calling tubes. The sound waves consequently reach this disk 23 both through the large central and also through the surrounding smaller holes and in various ways. At the back of the 60 membrane disk 23 there is provided a felt disk 24, the form of which, for example, can resemble that of a wheel with six spokes (see Fig. 6). This division corresponds to the division into six parts of the carbon 65 pieces 25 in the usual microphones. The

spoke-like cross pieces lie opposite the spaces between the carbon pieces 25, so that the holes 22 always open into intermediate spaces between the spokes, which divide the space behind the membrane disk 23. Carbon 70 powder 26 is filled in between the spokes. It has been demonstrated that this arrangement produces much more understandable sounds than such a one without holes 22 and without felt disk 24. The application of a 75 felt disk behind the membrane disk is not new, but it is new to divide the felt disk in a manner corresponding to the number of holes.

Both improvements, first the displacement 80 of the transmitting microphone 8 with relation to the receiver 5, and second the providing of the receiving microphone with the new cover 20 and the described felt disk 24, allow the application of much more 85 powerful batteries than was formerly possible. Hitherto a potential of three volts was considered as the highest applicable potential for the battery. Further increase of the potential gave no advantage, since at 90 the same time disturbing concomitant sounds arose which made impossible an understanding of the transmitted speech sounds.

With the aid of the present improvements 95 one can employ much stronger batteries and at the same time perfectly control the sound, by adjusting from time to time the distance of the receiving microphone from the listening apparatus; whereby conversation is rendered possible over much greater distances 100 than formerly.

According to the construction indicated in Fig. 8 there are two hearing devices indicated at 8^a and 8^b arranged in series and the number of such listening devices may 105 be still further increased.

The suppression or weakening of the disturbing harmonics is effected in a very peculiar way. The hole 28 in the listening telephone held to the ear is covered on its 110 inner side by pasting over it a thin sheet of paper, which acts to absorb or weaken the disturbing harmonics. On the passage of the fundamental sounds, on the other hand, the paper has far less influence. The sheet 115 of paper would not look as well on the outside, but the effect would naturally be the same.

I claim as my invention:—

1. Means for rendering a telephone applicable to varying distances, comprising a receiving device inserted in a branch from the circuit of said telephone and a magnifying means detachably attached to said receiving device and magnifying the sound received therein, said magnifying means comprising a membrane and a cover located on the side of the membrane toward said receiving device and having a number of small holes through it, said holes being flared toward 120

125 130 135

the membrane, a felt disk on the other side of the membrane and having holes in it in line with the holes in the cover, and carbon powder located in said holes in the felt disk.

2. Means for rendering a telephone applicable to varying distances, comprising a receiving device inserted in a branch from the circuit of said telephone and a magnifying means detachably attached to said receiving device and magnifying the sound received therein, said magnifying means comprising a membrane and a cover located on the side of the membrane toward said receiving device and having a number of small holes through it, said holes being flared toward the membrane, a felt disk on the other side of the membrane and having holes in it in line with the holes in the cover, carbon powder located in said holes in the felt disk, and means for adjusting said receiving device and said magnifying device toward and away from each other.

3. Means for rendering a telephone applicable to varying distances, comprising a receiver and a second receiving device inserted in a branch from the circuit of said first receiver and a magnifying means detachably attached to said receiving device and magnifying the sound received therein, said magnifying means comprising a membrane, a source of current of suitable strength for rendering audible currents of feeble strength received from a long distance, and a cover located on the side of the membrane toward said receiving device, and means for adjusting said receiving device and said magnifying device toward and away from each other, in order to render distinct sounds received from distances less than the extreme distance to which the strength of said source of current is suited.

In witness whereof, I have hereunto signed my name in the presence of two subscribing witnesses.

ROBERT LAGUS.
